UNITED STATES PATENT OFFICE.

JEAN CASTRO AND EDWARD CASTRO, OF NEW YORK, N. Y., ASSIGNEES TO LESHER,
WHITMAN & CO., INC., OF NEW YORK, N. Y., A CORPORATION OF NEW YORK.

DESIGN FOR A TEXTILE FABRIC.

Application filed February 14, 1929. Serial No. 30,070. Term of patent 3½ years.

To all whom it may concern:

Be it known that we, JEAN CASTRO and EDWARD CASTRO, citizens, respectively, of the United States, residing at New York city, in the county and State of New York, have invented a new, original, and ornamental Design for a Textile Fabric, of which the following is a specification, reference being had to the accompanying drawing, forming part thereof.

The figure is a plan view of a textile fabric, showing our new design.

We claim:

The ornamental design for a textile fabric, as shown.

JEAN CASTRO.
EDWARD CASTRO.
